US00D973794S

(12) **United States Design Patent** (10) **Patent No.:** **US D973,794 S**
(45) **Date of Patent:** **** Dec. 27, 2022**

(54) **EXERCISING APPARATUS**

(71) Applicant: **Asobii Kabushiki Kaisha**, Osaka (JP)

JP	D1518468	3/2015
JP	D1544381	2/2016
JP	D1556738	8/2016

(72) Inventor: **Shoten Sanjo**, Osaka (JP)

(73) Assignee: **ASOBII KABUSHIKI KAISHA**,
Osaka (JP)

(**) Term: **15 Years**

(21) Appl. No.: **35/512,029**

(22) Filed: **Dec. 16, 2020**

(80) **Hague Agreement Data**

Int. Filing Date: **Dec. 16, 2020**

Int. Reg. No.: **DM/211980**

Int. Reg. Date: **Dec. 16, 2020**

Int. Reg. Pub. Date: **Jun. 18, 2021**

(30) **Foreign Application Priority Data**

Jun. 18, 2020 (JP) 2020-012093D

(51) **LOC (13) Cl.** **21-02**

(52) **U.S. Cl.**

USPC **D21/692**
